UNITED STATES PATENT OFFICE.

HENRY DALLEY, JR., OF BROOKLYN, NEW YORK.

DESIGN FOR A BOTTLE.

SPECIFICATION forming part of Design No. 17,515, dated August 2, 1887.

Application filed July 7, 1887. Serial No. 243,685. Term of patent 14 years.

To all whom it may concern:

Be it known that I, HENRY DALLEY, Jr., of Brooklyn, county of Kings, and State of New York, have invented and produced a new 5 and original Design for Bottles, of which the following is a full, clear, and exact description, reference being had to the accompanying drawings, making part of this specification.

Figure 1 is a perspective view of my newly 10 designed bottle. Fig. 2 is a front elevation of the same. Fig. 3 is a horizontal section of the same through the line x x of Fig. 2.

The same letters refer to like parts in the different figures.

15 A B C D denote the different sides of the bottle, which are of equal or nearly equal width. d e f g denote the four vertical corners. h denotes the bottom of any one of the four sides; j the top of any one of the four sides.

20 Heretofore bottles have been made with rounded vertical pillars projecting from the various corners, and also with parallel sides and corners curved or rounded out beyond the plane of the sides.

25 The leading features of my invention consist in a bottle of generally rectangular shape and with equal sides, but with each union of the planes which form the sides, top, and bottom somewhat curved or rounded, said curves being entirely within the space which would be 30 inclosed within the extension of the planes proper to a meeting point or union.

The sides of the bottle are all plain—that is to say, without panels—and either entirely straight or very slightly curved, so as to give 35 a barely perceptible bulge or swell to them. Where the sides meet the bottom (h of the drawings) there are also curved or rounded edges. Where the top meets the sides (j of the drawings) there are also curved or rounded 40 edges precisely the same as at the vertical meetings of the sides. It will thus be seen that there is not a single well-defined angle in the entire bottle, but the union of all the sides, top, and bottom are short curves. Still, however, the general shape is that of a rectangular bottle, and one the general appearance of which differs in a marked degree from any one hitherto made, and could not be mistaken for any other previously invented. 45

Having thus described my design, I claim—

The design for a bottle herein shown and described, the same consisting of a bottle of generally rectangular shape, with equal sides and with rounded non-projecting corners and 55 sides throughout the entire structure.

In testimony whereof I have hereunto set my hand this 6th day of July, A. D. 1887.

HENRY DALLEY, JR.
